UNITED STATES PATENT OFFICE.

WILLIAM IRELAN, SR., OF SAN FRANCISCO, CALIFORNIA.

AUTOMATIC SAFETY-GUARD AND TRACK-CLEARER FOR UNDERGROUND CABLE RAILWAYS.

SPECIFICATION forming part of Letters Patent No. 363,394, dated May 24, 1887.

Application filed October 13, 1886. Serial No. 216,180. (No model.)

To all whom it may concern:

Be it known that I, WILLIAM IRELAN, Sr., a citizen of the United States, residing at San Francisco, in the county of San Francisco and 5 State of California, have invented a new and useful Combined Automatic Safety-Guard and Track-Clearer for Underground Cable Railways, of which the following is a specification.

This invention relates to a guard and track-clearer connected to the forward end of a dummy or car operating automatically upon a fixed frame, the object of the same being to provide a guard and track clearer of such construction that when the impact is given the 15 person or animal so engaged by the track-clearer will not be injured or the car thrown or lifted from the track. I accomplish this object by the mechanism illustrated in the accompanying drawings, forming a part of this 20 specification, in which—

Figure 1 is an elevation of a dummy with my safety guard and track-clearer attached. Fig. 2 is also a view in elevation of the same. Fig. 3 is a plan or top view. Fig. 4 is a view 25 in elevation showing the guard and track-clearer hinged to the forward end of the car.

A represents a car or dummy, to the front end of which is connected a supporting-frame, B, either rigidly, as shown in Figs. 1 and 2, 30 or by a loosely-jointed connection, as shown in Fig. 4. This frame is so connected to the car that the lower face thereof will just skim the track and not come in contact with the rails even though the end of the car should be 35 come slightly tilted, as in passing over irregularities in the track.

The supporting-frame is curved or inclined upward from the outer end to its connection with the car-body, and the outer end or point 40 is a straight edge, so as to form a stop for the movable apron or track-clearer in its operation when coming in contact with an opposed object.

The body C of the track-clearer or apron is 45 constructed of a sheet of metal or other suitable materials, and is slightly curved, as shown. The shoe D, which is bolted or otherwise connected to it, may be made of some light strong wood, and is slanted or inclined off to beveled 50 angles, in the usual way, or in a similar manner

to that of ordinary track-clearers, while the inner edge is also a straight edge to correspond with the straight edge or stop of the supporting-frame above described, so that when the two opposed edges come in contact a shoulder or stop will be formed and limit the throw or backward movement of the apron against the shoulder of the supporting-frame and intermediate spring. 55

To the forward end of the supporting-frame 60 are attached the guiding-rods E E E, curved or bent to correspond with the curvature of the apron. These rods extend inward or backward and connect with the front end of the car or the supporting-frame, as the case may require. 65 Upon these rods the movable apron operates through the medium of the sleeves or guides F, passing up the inclined and curved guides when the shoe or apron strikes against an opposing object in its way. 70

In order to insure a better and more certain movement of the apron, however, and prevent friction of the parts, the friction-rollers F^x are employed. These rollers are pivoted within or upon the ends of the supporting-frame in 75 such a manner that the lower face of the curved apron will act or bear upon them when movement takes place in either direction, upward or downward.

In ordinary track-clearers for street-railways when the shock or impact takes place it is usually so great as to seriously injure, if not kill outright, the person struck, and in order to remedy this great defect I employ the two flat half-elliptic springs. The lower one (represented by the letter G) is clipped to the lower straight edge of the supporting-frame, and the ends thereof bear against the straight edge of the shoe of the movable apron. The counterpart of the spring G^x is clipped or bolted to the 80 front of the supporting-frame, with its end bearing against the upper edge of the apron, so that when the end of the toe or shoe strikes the object the apron will be crowded backward and upward along the curved guiding-rods 85 and cushion against the two springs and the shoulder formed by the two straight edges between the apron and supporting-frame, which movement will lower the end of the apron, so that it will just skim the track and pick up 90

the object or clear it away from the track of the car, the blow or impact being so light as not to seriously injure the person struck.

When the pressure is removed from the track-clearer, caused by the impact, the resilience of the two springs will force the apron back to its original position again for further protection. To lessen the force of the fall the face of the track-clearer may be lined with some yielding material, such as india-rubber or leather.

Having thus described my invention, what I claim, and desire to secure by Letters Patent, is—

15 1. In a track-clearer for street-railways, the combination, with the supporting frame, of the movable apron provided with the shoe, the guiding rods, and suitable guiding devices whereby the movable apron operates upon said rods, substantially as described.

2. In a track-clearer for street-railways, the combination of a jointed or fixed frame with an apron adapted to move upon curved guiding rods or ways against flat or half elliptic springs to receive the shock or impact and lower the point or toe of the apron, in the manner described.

3. In a track-clearer for street-railways, the combination of a jointed or fixed frame with an apron moving thereon upon curved guiding rods or ways, with or without friction-rollers, against resilient springs to receive the shock or impact and lower the point or toe of the apron, in the manner described.

In testimony that I claim the foregoing I have hereunto set my hand and seal.

WILLIAM IRELAN, SR. [L. S.]
